UNITED STATES PATENT OFFICE

CHARLES N. WAITE, OF RUMFORD FALLS, MAINE, ASSIGNOR TO THE ELECTRO-CHEMICAL COMPANY, OF SAME PLACE.

METHOD OF UTILIZING SALINE SOLUTIONS.

SPECIFICATION forming part of Letters Patent No. 558,241, dated April 14, 1896.

Application filed October 5, 1895. Serial No. 564,800. (No specimens.)

To all whom it may concern:

Be it known that I, CHARLES N. WAITE, a citizen of the United States, residing at Rumford Falls, in the county of Oxford and State 5 of Maine, have invented certain new and useful Improvements in Methods of Utilizing Saline Solutions, of which the following is a specification.

My invention has for its object an improved 10 method for the utilization of saline solutions. It is fully set forth in the following description, and its novel features are pointed out in the claim which is appended hereto.

In the production of chlorin and of caustic 15 by the electrolysis of a chlorid of an alkaline base the solution of chlorid is subjected, in an electrolytic cell, to the action of an electric current until the efficient working of the electrolytic cell is interfered with by the presence 20 of such a percentage of the hydrate or caustic as will decrease the efficiency of the current beyond the limit at which the cell may be economically operated. When this occurs, the solution in the cathode-compartment 25 of the cell is removed and new solution supplied. The solution removed has lost only about one-third of the chlorid, and thus there occurs a loss of a considerable portion of chlorid which cannot be economically employed in 30 the cell, owing to the presence of the hydrate or caustic.

In the production of chemical fiber, which is employed in the manufacture of paper, the wood fibers or chips are boiled in a digester 35 with liquor containing caustic in solution. As a result of this treatment the gum and resin in the wood are converted into a soap and the fiber is left-free. The fiber is then removed and the soapy liquor containing the excess of caustic is evaporated and roasted in a rotary furnace, yielding black ash, which is recausticised with quicklime and used over and over again, enough efficient caustic being added to make up for the loss in recovery.

45 By means of my process I utilize the solution which is drawn from the cathode-compartment of an electrolytic cell and which contains, as above stated, the chlorid of the alkaline base and a considerable percentage— 50 usually from six to eight per cent. of the hy-

drate of the base—by employing the said solution for the treatment of the wood fiber in the digesters in the production of chemical fiber. The presence in this solution of the chlorid—ordinarily chlorid of sodium—does not interfere with the use of the solution for this purpose. After the wood fiber has been boiled in this solution from the cathode-compartment of the electrolytic cell the fiber is washed and the soapy liquor containing salt and the excess of caustic is evaporated and the residuum roasted. The black ash which results from the roasting contains salt and the carbonate of soda and some impurities, such as coal, tarry matters, and the like. I now treat this 55 ash by lixiviating with a limited amount of water, which results in the removal of the larger proportion of the carbonate of soda. The latter, being more soluble than the salt, will go into solution first. The salt and the 60 remainder of the carbonate of soda containing the tarry matters, &c., are then dissolved and enough quicklime is added to causticise the carbonate of soda. The resulting dirty 65 solution is then run into the cathode side of the electrolytic cell and subjected to electrolytic action until there is again produced in it such a percentage of the hydrate or caustic as will interfere with the efficient and economic working of the cell by decreasing the 70 efficiency of the current beyond the economic limit. The dirty solution referred to should be used only in the cathode side of the cell, since the presence in the anode-compartment of the cell of a small percentage of caustic and 75 of the tarry matters would destroy the efficient working of the cell. When in the operation of the electrolytic cell the solution in the cathode-compartment again contains a sufficient percentage of the hydrate to interfere 80 with the working of the cell, the liquor is again used in the digesters for the treatment of fiber, and the process is repeated. 85 By this method the chlorid, if chlorid of sodium be employed, can be used up entirely, 95 only enough salt being added to make up for soda lost in the fiber from imperfect washing without any loss of efficiency in the electrolysis and with no waste of salt. My process is particularly desirable in localities where pa- 100

per-making is carried on and where salt is expensive, since by its employment a considerable saving is effected.

What I claim is—

- 5 That improvement in the utilization of saline solutions which consists in subjecting the solution to electrolysis in an electrolytic cell, and producing chlorin and hydrate, then placing the solution containing the hydrate in a digester with wood fiber and boiling the fiber therein, then separating the wood fiber from the liquor and evaporating the latter, then roasting the residuum and producing black

ash, then lixiviating to remove a portion of the carbonate from the ash, then dissolving 15 the residuum causticizing it with quicklime and subjecting it to electrolytic action in the cathode-compartment of an electrolytic cell, substantially as described.

In testimony whereof I affix my signature 20 in presence of two witnesses.

CHARLES N. WAITE.
